UNITED STATES PATENT OFFICE.

GEORG LAMMERMANN, OF NUEREMBERG, GERMANY.

CARROUSEL SWING.

Application filed December 13, 1922. Serial No. 606,654.

To all whom it may concern:

Be it known that I, GEORG LAMMERMANN, a subject of Germany, and a resident of Pfalzerstrasse 60, Nuremberg, Germany, have invented a new and Improved Carrousel Swing, of which the following is a full, clear, and exact description.

The invention relates broadly to amusement devices, and more particularly provides what may be termed a carrousel-swing for indoor or garden or other outdoor use.

One object is to provide a novel structure particularly adapted for use as a child's swing.

Another object is to provide such a swing, of simple and inexpensive construction, in which means are provided whereby the seat or passenger support of the swing is suspended in such a way that what may be termed a gyro-suspension is given, and the swinging movements of the seat may be controlled at will from a point below the point of suspension, and preferably by the child itself when seated in the swing, in order to vary the paths of swinging by moving the seat endwise as well as sidewise in different combinations during swinging.

The essence of the invention then may be described briefly as involving the provision of a carrousel-swing including a gyro-suspension for a passenger seat, with such suspension adapted to have certain of its elements temporarily re-adjusted at will to permit the seat to gyrate variously and to swing when desired like a pendulum.

The invention will be more clearly understood from the following description, when taken in connection with the accompanying drawings, which show various embodiments of the invention as at present preferred, but only illustratively of course; the scope of protection contemplated being indicated by the appended claims.

In these drawings:

Fig. 1 shows a complete swing constituting the embodiment of the invention at present most preferred;

Fig. 2 is a side elevation of the gyro-suspension shown in front elevation in Fig. 1;

Fig. 3 shows in front elevation another embodiment of the gyro-suspension;

Fig. 4 is a view similar to Fig. 2, but showing the parts of Fig. 3; and

Fig. 5 illustrates still another embodiment of the gyro-suspension.

Similar reference characters refer to simi-

lar parts throughout the several views of the drawings.

Referring to Figs. 1 and 2, the gyro-suspension includes, as the main suspending member thereof, a rod-like member 1 carrying at its top a hook, such member 1 being surrounded by a noose sleeve 2, which sleeve is what may here be termed the main rotatable member of the suspension.

The two main members just described are parts of a suspending structure for a swing-seat or passenger support 3, such suspending structure including, in addition, the principal elements of a cross bar 4 fast on sleeve 2 and from the opposite ends of which are hung chains or ropes 5 suspending the seat, and means for rotating at will the sleeve and hence the cross bar and seat.

In the present case, such gyrating means includes a beveled gear 6 fixed on member 1 just below sleeve 2. Gear 6 meshes with a similar gear 7 fast on a stud-shaft 8 journaled at one end in cross bar 4 and at its other end in a bracket 9 secured at its upper portion to the upper end of sleeve 2. Fixed on this stud-shaft is also a grooved disk 10, in the groove of which is adapted to run an endless cable 11, this cable being guided to frictionally engage the disk at all times so that a pull on the cable causes the disk to be rotated in one or the opposite direction at will; such guiding means for the cable comprising a pair of rollers 12 each carried on a bracket 13 on the cross bar, the two lower ends of the brackets which carry the rollers being joined by a strap 14.

In operation, the gyro-suspension is, of course, controlled as to its varieties of gyration by means of such cable. It will be understood that the seat 3 may not only be given a spinning motion while it swings like a pendulum, but will also have a tendency, when cable 11 is pulled with some abruptness, to travel through an arcuate path into and out of the vertical plane through which the seat describes an arcuate path when swinging merely as a pendulum; thus causing the seat to swing by endwise, as well as sidewise, movements, and so set up a gyroscopic movement somewhat like that of a circle swing.

It will be noted from Fig. 1 that the various gyroscopic controls above referred to may be exercised by the child seated in the swing; to facilitate which the lower loop of the cable passes under a roller 15.

journalized in an open topped receptacle 16 connected at its bottom, by means of a spring 17, to a cable 17^a or the like arranged across the front of the swing-seat.

5 Referring to the modification of Figs. 3 and 4, it will be seen that the same general result is obtained, and by somewhat similar construction to that of Figs. 1 and 2. Here also the sleeve 2 is loose on member 1; and 10 this member 1 is again the main suspending member and the sleeve 2 is again the main rotatable member. Instead of the beveled gear construction of Figs. 1 and 2, however, a grooved disk 10^a is mounted fast on 15 member 1 above the sleeve, and the guiding rollers 12^a, for guiding and holding the endless cable 11 always in frictional engagement with the disk, are arranged as shown and carried on brackets 18 mounted on the 20 cross bar, these last mentioned brackets being braced by brackets 19 mounted on the sleeve.

The operation of the embodiment as just described is, of course, apparent.

25 Referring finally to Fig. 5, a main suspending member 20 is provided. The characteristic of this member 20, however, is that it, unlike the similar member in the previously described constructions, acts as 30 both the main suspending member and the main rotating member of the gyro-suspension. In Fig. 5, this member 20 has a cross bar 21 fast thereon and below the cross bar the member 20 terminates in an eye 22 with 35 which is swiveled the bight of a loop member 23 carried at the upper end of a rod 24, in a manner which will be well understood from the drawing. This rod may carry a suitable cross bar 25 at its lower 40 end to facilitate manual rotation of the rod, thereby to cause similar rotation of the main suspending member, and consequently similar rotation of the cross bar 21 and the swing-seat to be suspended therefrom.

45 I would state in conclusion that while the illustrated examples constitute various practical embodiments of the present invention, the same is not to be limited strictly to the exact details herein illustrated, since 50 manifestly such details may be considerably varied without departure from the spirit of the invention as defined in the following claims.

I claim:

55 1. A carrousel-swing including a passenger-carrying support, and a suspending device therefor including a suspending structure; said structure including the combination of means for suspending the same and 60 the support so as to permit swinging of the

support, a member rotatable about the axis of said suspending means, a rotatable grooved disc, and means for causing simultaneous rotation of the disc and said rotatable member, said means including a flexible member engaging the groove of the disc, and guiding devices on the rotatable member also engaged by the flexible member, said guiding devices for holding the flexible member to the groove of the disc, whereby 65 when said flexible member is pulled, the disc is rotated, the rotatable structure is also rotated and the flexible member is nevertheless maintained in engagement with the groove of the disc. 70 75

2. The carrousel-swing defined in claim 1, wherein said flexible member is continuous.

3. A carrousel-swing including a passenger-carrying support, and a suspending device therefor including a suspending structure, said structure including the combination of means for suspending the same and the support for swinging the latter, a member rotatable about the axis of said suspending 80 means, means for at will rotating said member, and means for causing the support to rotate with said member; said member rotating means including a suspended flexible member movable in relation to the rotatable 85 member thereby to rotate said rotatable member, and guiding means including a grooved disc fast on the rotatable member and a grooved roller for maintaining the flexible member constantly in frictional engagement with the grooved disk. 90 95

4. The carrousel-swing defined in claim 1, wherein said disk is mounted for rotation on an axis substantially at right angles to the axis of rotation of said member, and 100 a pair of intermeshing bevel gears are provided one fixed to the disk and one fixed to said member.

5. A carrousel-swing including a passenger-seat, a gyro-suspension therefor, and 105 means including a flexible actuator operably connected to the gyro-suspension and having a length manipulable by an occupant of the seat for varying at will the degree of gyration of the seat including a suspended 110 gyro-actuator operable by an occupant of said seat, said gyro-suspension including a suspending structure, a structure rotatable thereon, and a suspension means for the seat hung flexibly from the last-mentioned 115 structure.

GEORG LAMMERMANN.
